HANGER

Harry Horwitz, Springfield, Mass.

Application July 19, 1934, Serial No. 735,968

2 Claims. (CL 223—62)

This invention relates to improvements in garment hangers and is directed more particularly to an improved garment hanger which has two oppositely-disposed supporting surfaces.

5 The invention has for a principal object the provision of a garment hanger which is adapted to support both sleeveless and sleeve-bearing garments. Devices of this class are usually provided with one or more arm members adapted 10 to fit under the shoulders of the garment in such a way that the garment hangs naturally as from the shoulders of the wearer of the garment. The hanger of this invention is adapted by reason of its novel construction to support garments which 15 do not have shoulders, as is the case with sleeveless dresses for example.

It is a further object of the invention to provide a garment hanger which is simple in form 20 so that it may be manufactured inexpensively and which is readily collapsible so as to facilitate ease in shipping and packing. That is to say, as contrasted with clothes hangers of usual form, the hook members of this invention may be collapsed from an upstanding position relative to the garment supporting part of the device 25 to a position substantially in alignment therewith so that there are no objectionably projecting parts.

Various other novel features and advantages 30 of the invention will be more apparent after a reading of the following description and reference will be had to the accompanying drawing wherein:

Fig. 1 is a plan view showing the hanger of the 35 invention in one supporting position;

Fig. 2 is a plan view showing the hanger of the invention in another supporting position;

Fig. 3 is an enlarged view showing certain features of the invention;

40 Fig. 4 is an enlarged sectional plan view on the line 4—4 of Fig. 1; and

Fig. 5 is a sectional elevational view of the supporting member on the line 5—5 of Fig. 2.

Referring now to the drawing more in detail, 45 the invention will be fully described.

In Fig. 1 there is shown a supporting member 2 which is preferably composed of a relatively thin and flat piece of material such as wood which is relatively light in weight and sufficiently 50 strong and rigid. This member includes a central main body portion of a certain height and outwardly extending arms 4 as shown.

These arms 4 extend in opposite directions and are so formed that when the member 2 is disposed as shown in Fig. 1, the marginal edges of

the arms which are uppermost curve outwardly and slightly downwardly and when the member is inverted so as to be disposed in the position shown in Fig. 2, the uppermost marginal edges of the arms curve slightly upwardly.

Thus when the supporting member is disposed as shown in Fig. 1, garments having sleeves such as coats and the like may be hung thereon with the garment hanging naturally. When it is desired to hang garments which have no sleeves but merely a neck portion the support 2 may be inverted so that the arms 4 curve upwardly and the garment is prevented from falling therefrom.

It is a distinctive feature of this invention that the hook member of the hanger is arranged for 15 pivotal movements relative thereto. This feature will now be described.

An opening 10 is provided through the body portion of the member 2 and this is preferably centrally disposed as shown. Slots 12 are provided in the support on opposite sides of the opening 10 and they extend inwardly towards the opening from the upper and lower marginal edges of the main body portion as shown.

These slots 12 are preferably in alignment with 25 one another and they also are preferably of an equal length and width, although this is not essential.

A hook member 20 which is preferably composed of wire or some other substantially rigid 30 yet bendable material includes a substantially straight body portion 24 having one end bent to form a loop portion 22 for engaging a peg, clothes hook, clothes line, or some other part, and its opposite end 26 bent over into parallelism 35 with the portion 24 in the form of a U having a transverse connecting portion 28.

The member 20 extends through the opening 10 in the supporting member so that the transverse portion 28 is pivoted therein. The portion 26 is as shown in Figs. 3 and 4 spaced from the main body portion 24 of the hook member a certain distance greater than the thickness of the support so that the hook member and support may swing freely relative to one another.

The arm 26 of the U is of a certain length so that when the body portion 24 of the hook is in alignment with either of the slots 12, the upper end portion of the part 26 is disposed opposite the slot. A retaining member 30 is provided and this preferably consists of a closed band which as shown is relatively longer than it is wide and is adapted to embrace the upper end portions of the U.

That is to say, the member 30 is of less width 55

than the width of either of the slots 12 and is of greater length than the distance between the outsides of the arms of the U-shaped portion. In this way, the retainer may slide downwardly 5 over the arms of the U and into a slot. In this position as shown in Figs. 1, 2 and 4 the retainer 30 co-operates with the sides of the slot into which it is placed to prevent the hook member 20 from swinging on its pivot 28.

10 As has been pointed out above, the opposite longitudinal edges of the supporting member 2 are of unlike contour so that the member may support both sleeve-bearing and sleeveless garments. The support may be turned to present 15 the desired edge uppermost and the pivoted hook member moved into locked position so that it extends vertically relative to the said desired edge.

The slots 12 extend inwardly towards one 20 another from the said longitudinal edges and they terminate in spaced relation as shown in Fig. 5. With the transverse portion 28 of the hook rotatable in the opening 10 and the shank portion 24 and extremity 26 in parallelism, the support 2 and hook 20 may swing relative to 25 one another in parallel planes to position the loop 22 at either side of the support. Then by sliding the lock member 30 into one of the slots so that it embraces the shank and extremity, 30 the hook may be locked against swinging.

35 While I have described the invention in great detail and with respect to a preferred form thereof, it is not desired to be limited thereto since many changes and modifications may be made therein without departing from the spirit and scope of the invention. What it is desired to claim and secure by Letters Patent of the United States is:

1. A clothes hanger of the class described 40 comprising in combination, a unitary substantially rigid longitudinally-extending supporting member provided with a central opening there-through and transverse slots extending inwardly from its longitudinal edges which terminate in 45 spaced relation at opposite sides of said opening, a hook member formed to provide a main body portion for extending outwardly from a longitudinal edge of the supporting member and a U-shaped inner end portion, the said U-shaped inner end portion consisting of the lower end 50 of the main body portion disposed at one side of aid supporting member, an intermediate pivot portion passing through the opening therein and an extremity at the other side of the supporting

member in parallel spaced relation with respect to said lower end of the main body portion, and a lock member in the form of a closed band 5 slidable on the body portion of said hook member which is adapted to embrace said extremity of the hook member and is receivable in either of said slots, all adapted and arranged whereby said hook member may be swung relative to said supporting member in planes parallel thereto to position the main body portion of the hook member so that it extends outwardly from a longitudinal edge of the supporting member and may be locked in either of said positions by embracing the extremity by the lock member and sliding the same into the slot at the edge 15 of the support from which the body portion extends.

2. A clothes hanger of the class described comprising in combination, a unitary substantially rigid supporting member having one longitudinal edge curved concavely and the opposite longitudinal edge curved convexly, said member being provided with a central opening there-through and transverse slots extending inwardly from said longitudinal edges which terminate in spaced relation at opposite sides of said opening, a hook member formed to provide a main body portion for extending outwardly from one of the longitudinal edges of the supporting member and a U-shaped inner end portion, the said 30 U-shaped inner end portion consisting of the lower end of the main body portion disposed at one side of said supporting member, an intermediate pivot portion passing through the opening therein and an extremity at the other side 35 of the supporting member in parallel spaced relation with respect to said lower end of the main body portion, and a lock member in the form of a closed band 40 slidable on the body portion of said hook member which is adapted to embrace said extremity of the hook member and is receivable in either of said slots, all adapted and arranged whereby said hook member may be swung relative to said supporting member in planes parallel thereto to position the main body portion of the hook member so that it extends outwardly from one of said longitudinal edges of the supporting member and may be locked in either of said positions by embracing the extremity by the lock member and 45 sliding the same into the slot at the edge of the support from which the hook member extends.

HARRY HORWITZ.
